(57) **CLAIM**

The ornamental design for an exercise apparatus as shown and described.

DESCRIPTION

FIG. 1 is a front perspective view showing my new design;
FIG. 2 is another perspective view thereof;
FIG. 3 is yet another perspective view thereof;
FIG. 4 is yet another perspective view thereof;
FIG. 5 is a top plan view thereof;
FIG. 6 is a bottom plan view thereof;
FIG. 7 is a front view thereof;
FIG. 8 is a rear view thereof;
FIG. 9 is a right-side view thereof;
FIG. 10 is a left-side view thereof;
FIG. 11 is a perspective view of the exercise apparatus in a closed state;
FIG. 12 is another perspective view thereof;
FIG. 13 is yet another perspective view thereof; and,
FIG. 14 is yet another perspective view thereof.
The broken lines show structure that form no part of the claimed design.

1 Claim, 14 Drawing Sheets
